Primary Examiner — Jennifer Rivard

(74) Attorney, Agent, or Firm — Daniel M. Cohn;
Howard M. Cohn(57) **CLAIM**

The ornamental design for a haircut fade guide, as shown and described.

DESCRIPTION

FIG. 1 is a perspective view of a haircut fade guide showing my new design;

FIG. 2 is another perspective view thereof;

FIG. 3 is a left view thereof;

FIG. 4 is a right view thereof;

FIG. 5 is a rear view thereof;

FIG. 6 is a front view thereof;

FIG. 7 is a top plan view thereof;

FIG. 8 is a bottom plan view thereof; and,

FIG. 9 is another perspective view illustrating the claimed design in a state of use.

The broken line disclosure of a head in FIG. 9 illustrates the environment of the haircut fade guide and forms no part of the claimed design.
